UNITED STATES PATENT OFFICE

153,840

DESIGN FOR A PERFUME ATOMIZER

Harry Anbender and William J. Weinstein,
Detroit, Mich.

Application March 22, 1947, Serial No. 137,820

Term of patent 7 years

(Cl. D83—1)

To all whom it may concern:

Be it known that we, Harry Anbender and William J. Weinstein, citizens of the United States, residing at Detroit, in the county of Wayne and State of Michigan, have invented a new, original, and ornamental Design for a Perfume Atomizer, for which the following is a specification, reference being had to the accompanying drawing, forming part thereof, in which:

Figure 1 is a front elevational view of the perfume atomizer, showing our new design.

Figure 2 is a plan view thereof.

Figure 3 is a left end elevational view thereof.

Figure 4 is a right end elevational view thereof.

Figure 5 is a front elevational view thereof with its cover opened.

Figure 6 is a bottom plan view thereof; and

Figure 7 is a plan view of the perfume atomizer with the top opened.

We claim:

The ornamental design for a perfume atomizer, substantially as shown.

HARRY ANBENDER.

WILLIAM J. WEINSTEIN.
